UNITED STATES PATENT OFFICE

DAVID W. DOWNHOUR, OF UNION FURNACE, OHIO

GRAIN-DOOR CONSTRUCTION

Application filed February 27, 1929. Serial No. 343,137.

This invention relates to improvements in car doors of the type used in connection with railroad cars for holding grain and similar material.

5 One of the objects of the invention is to provide a door of such construction that the loss of grain is averted during the transportation thereof from storage to its destination.

Another object of the invention lies in the 10 provision of a door of this character which is made up of sections interfitting one another so that the same may be quickly and easily assembled and held in place without the use of spaced fittings such as guides, angles, bolts 15 or other devices.

The invention further contemplates the 20 provision of a grain door construction which is simple and novel in its construction, strong, durable, cheap and economical to manufacture.

With these and other objects in view the invention consists in certain other features of construction, combination and arrangement of parts to be hereinafter fully described, illustrated in the accompanying drawings and specifically pointed out in the appended claim.

For a further understanding of the invention reference is to be had to the following 25 description and the accompanying drawing, wherein:

Figure 1 is an elevation of a door structure taken from a viewpoint within the car body,

Figure 2 is a vertical sectional view taken 30 on the line 2—2 of Figure 1,

Figure 3 is a horizontal sectional view taken on the line 3—3 of Figure 1,

Figure 4 is a side elevation taken from a 35 viewpoint outside of the car body showing the door structure in its operating position,

Figure 5 is a perspective view showing a pair of door sections,

Figure 6 is a slightly modified form of a door section.

40 Referring more particularly to the drawings, the numeral 1 designates the side wall of the car body provided with a door opening 2 located as usual above the floor 3. Located at each side of the door opening 2 are the door posts 4 of customary construction. The

door structure is composed of a plurality of independent sections 5 formed from wide single boards 6 or of a plurality of narrow board sections 7, as disclosed in Figure 6 of the drawing.

55 The door sections 5 forming the door structure are of lengths greater than the width of the door opening 2 and are so placed on the inside of the car that the ends of said sections abut against the posts 4. Thus the smooth side of the door is on the inside or towards the grain in the car. Each section is provided with an upright 8 at each end thereof which are of a height equal to the width of the board or boards forming the door sections 5. Also secured to each section and positioned between the uprights 8 is a strip 9 which is arranged to extend a distance above the door section proper and adapted to form a flange overlapping the lower portion of the nearest upper door section and to also be positioned between the uprights 8 of the said upper section. Thus the sections are interlocked and longitudinal movement between the same is prevented.

70 To avoid shifting of the door in a longitudinal direction with respect to the door opening 2 the lower section 5 of the door may be nailed in place as indicated at 10. This is the only fastening means necessary to hold the door in place due to the interlocking of the sections as previously described and also due to the pressure exerted by the grain or other material in the car.

75 In the modified form disclosed in Figure 6 additional strips 11 may be nailed in place to cover the meeting edges of the boards 7 to prevent grain from leaking and spilling out therethrough.

80 From the foregoing description it will be seen that there is provided a grain door structure which is very simple in its construction and one that can be very quickly and easily assembled to close the door opening of the car and also capable of being readily taken apart and removed so as not to obstruct the door opening in any way during other uses of the car.

85 What is claimed is:

90 In a car door comprising a plurality of

100

separable sections arranged one above the other to cover a door opening, each of the sections being formed with an upright at each end thereof adapted to butt against the inner marginal side edges of the door opening, a strip provided on one of the longitudinal edges of each of said sections, said strip extending a distance above said edge and adapted to overlap the lower edge portion of the upper adjacent section and of such length as to fit in between the uprights of the upper adjacent section, the strips forming joints between the sections and serving to hold the sections in an operative alignment with respect to each other.

15 In testimony whereof I affix my signature.
DAVID W. DOWNHOUR.
